UNITED STATES PATENT OFFICE.

JOHN MANNING VAN HEUSEN, OF BOSTON, MASSACHUSETTS, ASSIGNOR TO VAN HEUSEN PRODUCTS, INC., A CORPORATION OF DELAWARE.

COLLAR.

Application filed July 23, 1921. Serial No. 486,934.

To all whom it may concern:

Be it known that I, JOHN MANNING VAN HEUSEN, a citizen of the United States, residing at Boston, in the county of Suffolk, 5 State of Massachusetts, have invented certain new and useful Improvements in Collars; and I do hereby declare the following to be a full, clear, and exact description of the invention, such as will enable others skilled 10 in the art to which it appertains to make and use the same.

This invention relates to improvements in soft folding or turn down collars made up of heavy fabric such as multiply interwoven 15 fabric woven in a single piece and provided with a weakened edge fold portion or edge fold portion of increased flexibility, that is, an edge fold portion woven in the fabric at which the collar will normally tend to 20 fold.

According to the present invention, the edge fold portion is made by weaving the fabric in a folded condition, so to speak, that is, so that the portions of the fabric 25 that go to make up the neckband and turn down portion of the collar respectively, are woven in much the same relative position to each other that they are in the finished collar when folded, and so that the normal 30 shape of the edge fold portion of the fabric approximates that of the folded collar.

The fabric can be woven so that the portions thereof on the two sides of the edge fold portion may be the same length, but it 35 is much more advantageous to weave the fabric so that the portion on one side of the edge fold portion is woven longer than the other, so that the fabric of which the collar is made will not only tend to assume a 40 folded condition, but will also tend to assume a curvilinear shape, and so that the turn down portion of the collar will not be too close to the neckband portion when the collar is worn, that is, so that there shall be room 45 for free play of the neck-tie between the neckband and turn down portions of the collar. When the collar is made from such a fabric, in the manner hereinafter described, the collar will be shaped so that it 50 will normally tend to assume a folded curvilinear shape.

The fabric of which the collars are made is multiple-ply interwoven fabric of sufficient thickness and stiffness to present a smooth appearance without flimsiness. The 55

fabric may thus be two-ply interwoven fabric or three-ply interwoven fabric, or two-ply interwoven fabric woven with an intermediate filling layer.

The invention will be described more in detail in connection with the accompanying drawings which illustrate more or less diagrammatically the collar and the collar fabric, as well as the method of weaving the fabric.

In the accompanying drawings,

Fig. 1 is a diagrammatic illustration of a completed collar embodying the invention;

Fig. 2 is an enlarged sectional view of the edge fold portion of the collar; and

Fig. 3 is a sectional view of the fabric showing how it may be woven.

The collar illustrated is made up of the neckband portion 1 and folding or turn down portion 2, the neckband having the 75 usual end tabs, one of which is illustrated at 3 and is provided with the usual button-hole 4.

Fig. 2 illustrates the normal form of the fabric of which the collar is made. That is, the fabric is woven so that the outer ply or plies are longer than the inner ply at the edge fold portion of the collar. In other words, the neckband and the folding portions 1 and 2 of the fabric come together at a relatively sharp angle approximating that of the angle of the neckband and turn down portion of the collar when worn. It will thus be noted that in Fig. 2 the outer 80 ply of the two-ply fabric is longer than the inner ply at the fold portion of the collar indicated at 5. As a result, the collar fabric and the collar made therefrom fold more readily at the fold portion thus provided, giving, in effect, a weakened fold at this 85 point.

One method of weaving the collar fabric is illustrated diagrammatically in Fig. 3. The fabric illustrated in this figure is a flat tubular fabric with the upper and lower 100 portions of the fabric coming together at a sharp angle at their outer edges 8. In the particular form shown in Fig. 3 the lower fabric 6 is straight in cross-section and the upper fabric 7 is raised somewhat at its 105 central portion. In weaving the fabric, the fabric can be woven as a continuous fabric, that is, as a flat tubular fabric, with a normal section such as that illustrated in Fig. 3, or even with the upper and lower portions 110

of the fabric flat and in close proximity to each other, that is, without having the central portion of the upper fabric 7 raised in the manner shown.

5 In order for the collar to have a curvilinear shape, so that the edge fold portion will be curvilinear in the finished fabric and collar, one portion of the fabric is woven longer than the other. The upper portion 7 of the tubular fabric can thus be cut at its central portion 9 at a short distance from the point at which the cloth is formed by the "heating up" action of the lay beam, and the cut edges and intermediate portion of the fabric 7 can then be pulled at a slightly faster rate than the lower portion 6 of the tubular fabric, so that the portion 7 will be woven longer at the middle, that is, near the point 9, than it is at the fold portion 8. The fabric can be woven progressively longer from the fold portion 8 to the central portion at which it is cut at 9. Similarly the lower fabric 6 can be woven progressively shorter from the edge fold portion 8 to the central portion indicated at 10, and the fabric can be cut at 10 at a short distance from the point where the fabric is formed, to permit this decrease in length of the fabric; or the portion 6 can be woven progressively shorter from the fold portion 8 to the point 10 and the portion 7 can be woven progressively longer from the fold portion to the point 9. In order to do this both the upper and lower portions of the tubular fabric may be cut at the central portions 9 and 10 thereof. The folded fabric comprising the portions 6 and 7 on one side of the cut tube may then be opened out flat and passed over a conical take up roll which draws the warp threads on one side of the fabric faster than the warp threads on the other side, and the speed at which the said warp threads are drawn through will vary progressively from one extremity 10 of the unfolded fabric to the other extremity 9. Similarly the other half of the tubular fabric may be passed over another conical take up roll in order that one side of the fabric will be woven longer than the other. In this way the fabric is woven in a curvilinear form so that the collar made therefrom will have a curvilinear set. Also the edge fold portion 8 being woven in a folded position will tend to remain in that position and will provide a natural fold portion in the collar.

When the fabric has been woven in the manner above described the collar blank can be cut therefrom, and the edge of the collar blank may be provided with a suitable binding, for example, an edge binding such as described in my prior Patent No. 1,254,294. When the buttonholes are then made in the fabric the collar is finished.

Inasmuch as the fabric is woven with a normal position of the neckband and folding portion thereof approximating that of the folded collar when woven, it will be evident that the collar will naturally tend to assume and retain its folded position, and, when unfolded, will more readily fold again at the edge fold portion. It may accordingly be considered that the fabric is woven in a folded position, so to speak, although the collar can readily be unfolded, and, when unfolded, may present much the appearance of a flat piece of fabric. The weaving of the fabric at the edge fold portion may be the same as or similar to the weaving of the rest of the fabric, or the weaving may be modified at the edge fold portion, to further promote the tendency of the collar to fold at such portion as well as to promote the unfolding of the fabric to produce a fabric which is more or less flat in its unfolded form.

When, in addition, the fabric is woven with the turn down portion of the collar longer than the neckband portion, the collar will, as above pointed out, normally tend to assume a curvilinear shape as well as a folded shape, although the collar fabric may still be flat or approximately so.

When the fabric is woven in the manner above described and is cut along the central portion thereof at 9 and 10, the two portions of the fabric thus formed can both be used for the making of collars. That is, the fabric is a double fabric which, for every length equivalent to the length of a collar, furnishes material for two collars.

The different layers or plies of the multiply inter-woven fabric may be made of different material, for example, the outer ply may be made of a finer or more expensive material. So also, the collars may be constructed of different shapes and designs as will be readily understood. It will also be evident that, where the fold portion is curvilinear, that is, when the folding portion is woven longer than the neckband portion, an increased or decreased curvilinear effect can be obtained.

The edge fold portion of the fabric may or may not be interwoven. If the interweaving is omitted at the edge fold portion, this will somewhat modify the folding properties of the collar fabric and of the collars made therefrom, but the collar will still tend to fold at such edge fold portion, much the same as when the edge fold portion, as well as the remainder of the fabric is interwoven.

I claim:

1. In a folding or turn down collar made of multiple ply interwoven fabric in which the neckband and turn down portions thereof are woven in folded position.
2. A folding or turn down collar made up

of multiple ply interwoven fabric in which the neckband and turn down portions thereof are woven in a folded position, and with the turn down portion longer than the neckband portion, whereby the collar normally tends to assume a folded curvilinear shape.

3. A folding or turn down collar made up of a neckband portion, a turn down portion, and an edge fold portion of multiple ply interwoven fabric and having the inner ply of the fabric at the edge fold portion woven shorter than the outer ply.

4. A folding or turn collar made of one piece of multiple ply interwoven fabric comprising a neckband portion, a turn down portion and an edge fold portion, with the outer ply of the edge fold portion woven longer than the inner ply thereof so that the collar tends to assume a folded position, and with the turn down portion woven longer than the neckband portion.

5. The method of producing a collar fabric which comprises weaving a multiple ply interwoven fabric in a folded shape approximating that of the folded collar and cutting the collar from the fabric thus woven.

6. A foldable article of wearing apparel made of woven integral fabric comprising an outer and an inner ply, some of the warp threads of the outer ply being interwoven with the weft of the outer ply to produce an area of fold of an augmented warp tending to assume a natural bend, and the weft threads of the inner ply beneath the same tying and confining said augmented warp at the fold area.

7. A foldable article of wearing apparel made of woven integral fabric comprising at least two plies, there being on the outer surface of the fold area thereof, when the article is laid flat, a bulged or convexed zone which gives the said article a tendency to fold at and along said bulged or convexed zone.

45 8. A foldable article of wearing apparel made of woven integral fabric comprising at least two plies, there being, when said article is laid flat, a bulged or convexed zone on the

outer surface of the fold area thereof, but not on the inner surface of said fold area, whereby the said article has a tendency to fold at and along said bulged or convexed zone.

9. A folding or turn-down collar made up of a neckband portion and a turn-down portion of multiple ply interwoven fabric woven integral with each other, said fabric being so woven that the collar tends normally to assume a semi-folded position with the upper edge of the neckband portion and the upper edge of the turn-down portion at an angle to each other, and thus forming a line along which the collar naturally folds.

10. A folding or turn down collar made up of a neckband portion and a turn-down portion of multiple ply interwoven fabric woven integral with each other, said fabric being so woven that the collar tends normally to assume a semi-folded position with the upper edge of the neckband portion and the upper edge of the turn-down portion at an angle to each other, and thus forming a line along which the collar naturally folds, the turn-down portion being woven longer than the neckband portion.

11. A folding or turn down collar made up of a neckband portion and a turn-down portion of multiple ply interwoven fabric united by an edge fold portion of which the weft threads of the outer ply will be under greater tension when the fabric is folded and the weft threads of the inner ply under greater tension when the fabric is unfolded.

12. A folding or turn down collar made up of a neckband portion and a turn-down portion of multiple ply interwoven fabric united by an edge fold portion of which the weft threads of the outer ply will be under greater tension when the fabric is folded and the weft threads of the inner ply under greater tension when the fabric is unfolded, and with the turn down portion woven longer than the neckband portion.

In testimony whereof I affix my signature.

JOHN MANNING VAN HEUSEN.
